UNITED STATES PATENT OFFICE.

ALBERT T. KELLER, OF BALTIMORE, MARYLAND.

DOUBLE HOTBED.

1,315,670.

Specification of Letters Patent.

Patented Sept. 9, 1919.

Application filed March 27, 1918. Serial No. 225,069.

To all whom it may concern:

Be it known that I, ALBERT T. KELLER, a citizen of the United States, and a resident of Baltimore, in the city of Baltimore and State 5 of Maryland, have made a new and useful Invention in Double Hotbeds, of which the following is a specification.

This invention relates to the steel industry and particularly to hot beds for handling 10 long slender shapes during the cooling thereof.

An object of this invention is to provide a hot bed which shall, for all practical purposes, be perfectly balanced, that is, one in 15 which a load being lifted is in effect counterbalanced by a descending load in another portion of the device. By counterbalancing a load being lifted by one descending the power required for the operation of the bed 20 is reduced to a minimum and, as the entire load must be lifted a large number of times during a day's operation this cutting down of the required power is an important consideration.

25 A further object of this invention is to provide a bed in which the rods or bars shall be maintained in parallelism or in other words kept straight during their cooling, and this is secured by providing stationary 30 notched skids and lifting bars for moving the rods or bars from one series of notches to the other in a step by step manner.

A still further object is the provision of an apparatus which shall attain the desired 35 results in a simple and efficient manner without the use of parts liable to become worn and to require frequent replacement.

These as well as other objects which will readily be understood by those in this art 40 I attain by means of the apparatus described in the specification and illustrated in the drawings accompanying the same and forming a part of this application and throughout which similar elements are denoted by 45 like characters.

In the drawings, Figure 1 is an end elevation of a hot bed constructed in accordance with this invention, Fig. 2 is a plan view thereof, Fig. 3 is a section taken on 50 line 3—3 of Fig. 1 and Fig. 4 is a fragmentary end elevation of a portion of the feeding-in means for discharging the bars onto the hot bed. The hot bed of this invention may be termed a double hot bed, that is the 55 feeding-in rolls are located at the center of the bed and the material is discharged there-

from in opposite directions and is progressively moved in a step by step manner from the central feeding-in rolls to feeding-out rolls located on opposite sides of the feeding- 60 in rolls. The feeding-in rolls, the feeding-out rolls and the bed proper are duplicated on opposite sides of the center of the apparatus and are identical.

As illustrated in the drawings, it will 65 be seen that on suitable end supports 10, 10^a and center support 11 I mount transverse girders 12 and 13 on one side of the center and 12^a and 13^a on the opposite side. These girders serve to support the longitudinal 70 stationary skids 14 and 14^a, respectively. Skids 14 and 14^a in their upper surfaces are provided with notches 15 and 15^a and one end of each stationary skid is located in proximity to the feeding-in rolls 16 and 16^a while the other end of each skid is located in proximity to the discharge skids 17 and 17^a and the feeding-out rolls 18 and 18^a.

Alternating with the stationary skids are 80 lifting bars 19 and 19^a, respectively, mounted on girders 20—21 and 20^a—21^a which extend from end to end of the bed. Girders 20 and 21 are connected by links 22 and 23 to the outward extending arms of bell 85 cranks 24 and 25 while girders 20^a and 21^a are connected by links 22^a and 23^a to the outward extending arms of bell cranks 24^a and 25^a. The downward extending arms of bell cranks 24 and 25 are connected by 90 coupling rods 26 and pitmen 27 while the corresponding arms of bell cranks 24^a and 25^a are connected by rods 26^a and pitmen 27^a. The inner ends of the pitmen are connected to a crank 28 on a shaft 29 through 95 which motion is imparted by suitable slow-down gearing from a motor 30. The inner girders 21 and 21^a are provided with brackets 31 and 31^a which are connected by pitmen 32 and 32^a to a crank 33 on shaft 34 by 100 which motion is imparted through slow-down gearing by means of motor 30.

The rods such as shown at 35, Fig. 1, are received by the feeding-in rolls 16 and 16^a and are discharged in opposite directions 105 into the first notches of the stationary skids by means of levers 36 and 36^a to which motion is imparted by yoke 37 actuated by cam 38 mounted on shaft 34.

Shaft 29 which carries crank 28 and shaft 110 34 which carries crank 33 move in a clockwise direction. Lifting bars 19 in Fig. 1

are shown in their lowermost position while lifting bars 19^a are shown in their top or raised position. As operation of cranks 28 and 33 is continued lifting bars 19^a will move laterally and deposit rods 35 in the notches 15^a of stationary skids 14^a at the same time lifting bars 19 rise and lift the rods 35 from the notches 15 of stationary skids 14 and carry them forward to the next notch or away from shaft 34. The movement of the rods 35 progress in a step by step manner from the feeding-in rolls to the feeding-out rolls, the lifting bars on one side of the feeding-in rolls ascending while those on the other side are descending and since these are interconnected by the links and levers the weight of the moving parts and the load is practically balanced.

Having thus described my invention what I claim is—

1. In a hot bed, feeding-in means, a plurality of fixed longitudinal skids located on opposite sides of said means and provided with notches in their upper surfaces, lifting bars alternating with said skids, means for supporting the lifting bars on one side of said feeding-in means in balanced relation to those on the other side, and means for causing up and down motion of said lifting bars.
2. In a hot bed, feeding-in means, a plurality of fixed longitudinal skids located on opposite sides of said means and provided with notches in their upper surfaces,

lifting bars paralleling said skids, means for supporting the lifting bars on one side of said feeding-in means in balanced relation to those on the other side, and means for causing up and down motion of said lifting bars.

3. In a double hot bed, centrally located feeding-in rolls, mechanisms for transferring material in opposite directions from said feeding-in rolls, and means for connecting the transfer mechanism on one side of said feeding-in rolls with the transfer mechanism on the other side in such manner that the transfer mechanisms operate in balanced relation to each other.

4. In a double hot bed, centrally located feeding-in rolls, feeding-out rolls located on opposite sides of said feeding-in rolls, mechanism for transferring material in opposite directions from said feeding-in rolls to said feeding-out rolls, and means for connecting the transfer mechanism on one side of said feeding-in rolls with the transfer mechanism on the other side in such manner that the transfer mechanisms operate in balanced relation.

In testimony whereof, I have hereunto subscribed my name this 9th day of March, 1918.

ALBERT T. KELLER.
